US0D1094535S

(12) **United States Design Patent** (10) **Patent No.:** **US D1,094,535 S**
(45) **Date of Patent:** **** Sep. 23, 2025**

(54) **CASH REGISTER**

(71) Applicant: **SHENZHEN ZOLON TECHNOLOGY CO., LTD.**, Shenzhen (CN)

(72) Inventors: **Yuzhuo Wang**, Shenzhen (CN); **Deqiang Dong**, Shenzhen (CN); **Liting Lu**, Shenzhen (CN)

(73) Assignee: **SHENZHEN ZOLON TECHNOLOGY CO., LTD.**, Shenzhen (CN)

(**) Term: **15 Years**

(21) Appl. No.: **29/885,130**

(22) Filed: **Feb. 21, 2023**

(30) **Foreign Application Priority Data**

Nov. 10, 2022 (CN) 202230750456.5

(51) **LOC (15) Cl.** **18-01**

(52) **U.S. Cl.**

USPC **D18/12.3; D18/4.1**
